UNITED STATES PATENT OFFICE.

WILLIAM P. HARRIS, OF SOUTH CHICAGO, ILLINOIS.

AUTOMATIC ROLL-CALL FOR TELEGRAPH-LINES.

SPECIFICATION forming part of Letters Patent No. 280,616, dated July 3, 1883.

Application filed August 30, 1882. (No model.)

To all whom it may concern:

Be it known that I, WILLIAM P. HARRIS, a citizen of the United States of America, residing at South Chicago, in the county of 5 Cook and State of Illinois, have invented certain new and useful Improvements in Automatic Roll-Calls for Telegraph-Lines, of which the following is a specification.

It is customary in main offices of telegraph-lines during the night to "call" each office upon the circuit at stated intervals in order by the answers to this call to ascertain if all the operators are awake and on duty; and to do this automatically at any desired intervals 15 is the object of my invention; and to this end it consists, mainly, in the combination of a clock mechanism with a device for automatically making and breaking the circuit; and also in certain novel details of construction, 20 which will be hereinafter more fully described.

In order to enable others skilled in the art to which my invention appertains to make and use the same, I will now proceed to describe its construction and operation, referring 25 to the annexed drawings, in which—

Figure 1 is a rear elevation of my invention; Fig. 2, a similar view of the mechanism for actuating the call-wheel with said wheel removed, and Fig. 3 a side elevation of the 30 same.

Similar letters of reference denote similar parts throughout the several views.

A represents a clock mechanism of any of the well-known forms. This mechanism is secured to a board or back, B, and upon the rear end of the shaft which carries the hour-hand is secured a cam-wheel, C, which is supplied with cams of a number and form to correspond to the number of calls to be issued 35 each hour. The cam-wheel shown in the drawings has only two of these cams, being arranged to start the call every half-hour.

Below, or upon one side of the clock mechanism A, is secured a small frame, C', carrying 45 a rock-shaft, C². This rock-shaft is provided with two arms, c c', the first of which projects upward with its end resting against the edge of the cam-wheel C, and the arm c' extending at right angles to the other, and held in its 50 highest position by a spring, a, secured to the back B. As both arms are rigidly attached to the rock-shaft, this spring serves also to al-

ways keep the arm c in contact with the cam-wheel.

Immediately beneath the frame C' is a train 55 of gearing or spring-actuated clock-work, D, upon one shaft of which is a wheel, E, which I term a "call-wheel." The periphery of this wheel is provided with a series of projecting teeth, e e, of varying width, having spaces 60 e' between them, which correspond with the dots and dashes of the Morse alphabet, and are arranged in any desired combination to give a specified call when the wheel is re- 65 volved. This wheel is near its periphery provided with a beveled-edge opening, e², as seen in Fig. 1, the purpose of which will be presently understood.

Pivoted upon the end of a stud, F, secured to the back B, is a small sleeve, F', carrying 70 two arms, G G'. The arm G extends out over the side of the wheel E, and has its end bent to enter the spring e' when at rest or bear against the face of the wheel when in motion. The arm G' is bent around horizontally, and 75 rests against the face of a wheel, G², forming one of the train of gearing D. This wheel is provided with a pin or projection, g, which contacts with the arm G' and prevents the operation of the mechanism, the said arms being 80 held in this position by a spring, g', connecting them with the back B.

H is a rocking bar or lever pivoted upon a stand, H', and having one arm, h, extended rearward and bearing against the under side 85 of the arm e', while its other arm is bent and bears outwardly against the arm G. This lever H is held in this position by a spring, h², as shown in the drawings.

I represents a rod hanging from the arm c', 90 passing through a guide, i, and having its lower end in close relation to the periphery of the wheel G², as shown.

K represents a spring secured at one end on a stud, K', and having its other end bearing 95 against the edge of the call-wheel E with a force regulated by the tension-screw k under the spring.

P is a wire connecting the spring K with one pole of a battery or one part of an electric 100 circuit, and N is a wire connecting the frame of the mechanism D with the other pole or wire of a circuit.

The operation of this device is as follows:

The mechanism is secured in any convenient location in the main office, and the wires P N connected with the main line. If, now, the two clock mechanisms be wound up, the cam-wheel C, as it turns with its shaft, will throw out the upper end of the arm c and depress the outer end of arm c'. The depression of this latter arm causes the lever H (upon which it rests) to gradually force outward the arms G 5 and G' until the latter is free of the stop g upon the wheel G², which is then free to revolve. The time at which a call is to be made not having yet arrived, however, the stop g catches upon the lower end of the rod I, which has been 10 lowered as the arm c', from which it hangs, is depressed, and the cam C still revolves, throwing out the arm G until it is entirely free of the opening e² in the call-wheel. At this point the arm c passes over the end of the cam on 15 wheel C, and is immediately returned to its first position by the spring a. This withdraws the rod I, and the mechanism D immediately starts, revolving the call-wheel E. During the time the spring K rests against one of the teeth e, the 20 circuit is closed over wire P, spring K, wheel E, mechanism D, and wire N, to the main line, and when the spring is opposite one of the spaces e' the circuit is broken at that point, the alternate making and breaking of the circuit giving 25 a call over the wires to the different stations. When the wheel E has made a complete revolution, the spring - actuated arm G, resting against its face, springs into the opening e² and allows the arm G' to engage the stop g and hold 30 the gearing D at rest until again freed, as just described. The cams upon wheel C may of course be arranged to give one, two, or more calls every hour, as may be desired. The answers to the call may come in over the same 35 wires; but in case the main line should be in use for other purposes, I attach to the clock mechanism A a wire, b, and to the frame C' a wire, d, which forms a branch circuit to another line. The cam-wheel C, I then provide with 40 an insulating-point, f, upon which the arm c rests for a given time after dropping over one of the cams. The branch circuit is attached also to a receiver. When the arm is traveling over the cam, the connection is complete, 45 and all messages sent over this circuit pass through the mechanism just described; but when the arm c rests upon the insulating-point f this is cut out, and the answers are recorded 50

only through the receiver. During the night, the clock and call mechanism is thrown into 55 the main line, and all messages over the line pass through the mechanism. The call having been sent, the answers are all received upon a recorder or printer located in a branch circuit over the wires b d. The main line being 60 through the cam-wheel and the lever that rests upon it, an insulating-point in this wheel, upon which the lever lies for, say, five minutes after a call, will break the main line through the call-wheel and compel the current to pass 65 through the recorder. At the end of the five minutes, the lever having passed the insulation and again contacted with the metal cam-wheel, the circuit is again completed through the call-wheel till another call is given. 70

It is obvious that this device may be secured in a main office in any convenient position, and may be inclosed in a case in the face of which the clock-dial may show.

Having thus fully described my invention, 75 what I claim as new, and desire to secure by Letters Patent, is—

1. In a telegraphic circuit, the clock-work A, provided with a cam-wheel, C, in combination with a rock-shaft, C², having arms c c', 80 lever H, and arms G G', adapted to hold a call mechanism in a state of rest and start it at stated intervals, substantially as shown and described.

2. The combination, in a branch circuit, of 85 the rock-shaft C², having arms c c', cam-wheel C, provided with insulations f f on its periphery, with the clock-work A, and conducting-wires b d, substantially as shown and described.

3. An automatic telegraphic call arranged 90 in a circuit to be operated at stated intervals, consisting, essentially, of the clock-work A and cam-wheel C, connected by intervening mechanism, with an automatically - operated call-wheel, E, having its periphery notched to 95 make or break the circuit by contact with a spring, K, all constructed and arranged to operate substantially as and for the purpose set forth.

In testimony whereof I affix my signature in 100 presence of two witnesses.

WM. P. HARRIS.
